UNITED STATES PATENT OFFICE.

JEFF STOREY ELLISON, OF SAN ANTONIO, TEXAS, ASSIGNOR OF ONE-HALF
TO ORSON E. HOUGH, OF SAME PLACE.

PRICKLY-PEAR OR CACTUS BURNER.

SPECIFICATION forming part of Letters Patent No. 634,130, dated October 3, 1899.

Application filed February 21, 1898. Serial No. 671,128. (No model.)

To all whom it may concern:

Be it known that I, JEFF STOREY ELLISON, a citizen of the United States, residing at San Antonio, in the county of Bexar and State of Texas, have invented a new and useful Prickly-Pear or Cactus Burner, of which the following is a specification.

My object is to provide an improved portable gasolene-burner adapted to deliver an intense flame for destroying the prickles of the prickly-pear or cactus common to prairie land which may be operated with economy and facility.

The invention consists of a portable supply-tank having a suitable air-compressor and a supply-pipe connected thereto which is provided with a burner of novel construction, a pressure regulating or equalizing chamber, and other improved means set forth in detail hereinafter.

In the accompanying drawings, Figure 1 is a side view of the entire burner. Fig. 2 is a top view of the same.

Similar letters refer to similar parts throughout both views.

A is a cylindrical tank of convenient size, of galvanized iron or other suitable material, provided with sets of loops L on its sides, to which a strap can be connected to afford means for attaching the device to the person.

B is a screw-valve for filling the tank with gasolene.

C is an iron outlet-pipe inside the tank, which goes up from near the bottom of the tank and passes out of the top of the tank to a globe-valve E for opening and closing the burner at will. To the other end of the globe-valve E is fixed by a flexible tube F, of india-rubber or other suitable material, an iron pipe G, which is formed at the front into a coil I. This pipe-coil I is wound backward around the pipe, and the end H' of the pipe, which is closed by a screw-cap h, goes up in rear of and above the coil and has opposite the center opening of the coil a hole or the burner proper, J, for the outlet of the vapor. When cleaning of the coil is necessary, the cap h can be unscrewed to give access to the interior of the pipe. At about the middle of its length the pipe is provided with a pressure-regulating chamber H, which may be made of a piece of pipe, the one end connected

by a T-fitting to the pipe and the other end closed by a cap, or instead of the piece of pipe a pear-shaped pressure-regulating chamber 55 may be used.

K is a wire wick inside the whole length of the pipe, reaching into the coil, to carry the heat, after the coil is once heated by the flame, farther backward into the pipe. 60

D is a bulb air-pump, of india-rubber or other suitable material, with an air-valve d, connected by a flexible tube d' to a nipple on top of the tank A. This pump D is for pumping the air into the gasolene-tank A, 65 whereby the gasolene is forced through the pipe C into the burner, and as the pipe C reaches near the bottom of the tank A all the gasolene is forced out into the burner without changing the position of the tank A. The pressure having been pumped up in the tank, the oil is forced down the pipe and into the burner, and having been lighted the flame plays inside the coil, thus heightening the operation of vaporization. The wick conveys 70 the heat backward in the pipe, which further facilitates and assists vaporization, and the pressure equalizing or regulating chamber 75 equalizes the pressure in the pipe.

Having fully described my invention, what I claim, and desire to secure by Letters Patent, is—

1. In a device of the class described, the combination with a portable supply-tank, of a feed-pipe leading therefrom which is formed 85 into a heating or vaporizing coil having a portion provided with a burner which is adapted to direct its flame on the coil and terminating in a closed end which constitutes a vapor-pressure chamber.

2. In a device of the class described, the combination with a supply-tank, of a feed-pipe leading therefrom which is formed into a heating or vaporizing coil which terminates in an extended portion having a burner disposed away from the coil in position to direct 95 its flame within and upon the same and having a section located beyond the burner which is provided with a removable cap and serves as a vapor-pressure chamber.

JEFF STOREY ELLISON.
